SCRAP COMPRESSING APPARATUS FOR AN ELECTRIC FURNACE

Kunitoshi Tezuka, 34 7 Minami Sunamachi, Koto-ku,
Tokyo-to, Japan

Filed Oct. 3, 1966, Ser. No. 4,146

Term of patent 14 years

(Cl. D55—1)

FIG. 1

FIG. 2

FIG. 3

FIG-4

FIG. 5

FIG. 6

FIG. 1 is the front elevation view thereof;
 FIG. 2 is a rear elevation view thereof;
 FIG. 3 is a right side view thereof;
 FIG. 4 is a left side view thereof;
 FIG. 5 is a top plan view thereof; and
 FIG. 6 is a bottom plan view of the apparatus showing the new design thereof.

I claim:

The ornamental design for a scrap compressing apparatus for an electric furnace, as shown.
